(57) **CLAIM**

The ornamental design for fishing pliers, as shown and described.

DESCRIPTION

FIG. 1 is a perspective view of the fishing pliers according to the present invention.

FIG. 2 is another perspective view of the fishing pliers as illustrated in FIG. 1;

FIG. 3 is a side view of the fishing pliers as illustrated in FIG. 1.

FIG. 4 is another side view of the fishing pliers as illustrated in FIG. 1.

FIG. 5 is a bottom view of the fishing pliers as illustrated in FIG. 1.

FIG. 6 is a top view of the fishing pliers as illustrated in FIG. 1;

FIG. 7 is a front view of the fishing pliers as illustrated in FIG. 1;

FIG. 8 is a rear view of the fishing pliers as illustrated in FIG. 1; and,

FIG. 9 is a perspective view of the fishing pliers as illustrated in FIG. 1.

The material shown in dashed lines in the figures is not part of or a component of the claimed design.
